US00D649133S

(12) **United States Design Patent**
Goto et al.

(10) **Patent No.:** US D649,133 S
(45) **Date of Patent:** ** Nov. 22, 2011

(54) **PORTABLE TERMINAL**

(75) Inventors: **Eiji Goto**, Daito (JP); **Koji Horimoto**, Daito (JP); **Naoki Hirota**, Daito (JP)

(73) Assignee: **Kyocera Corporation**, Kyoto (JP)

(**) Term: **14 Years**

(21) Appl. No.: **29/389,500**

(22) Filed: **Apr. 12, 2011**

(30) **Foreign Application Priority Data**

Mar. 3, 2011 (JP) 2011-004820

(51) **LOC (9) Cl.** **14-03**
